ROTATABLE REFLECTOR FOR BICYCLES

Carl F. Gladen, Bay City, Mich.

Application March 12, 1953, Serial No. 24,006

Term of patent 14 years

(Cl. D72—1)

To all whom it may concern:

Be it known that I, Carl F. Gladen, a citizen of the United States of America, and a resident of Bay City, in the county of Bay and State of Michigan, have invented a new, original, and ornamental Design for a Rotatable Reflector for Bicycles, of which the following is a specification, reference being had to the accompanying drawing, forming a part hereof. -

In the drawing:

Fig. 1 is a perspective view of a rotatable reflector for bicycles showing my new design.

Fig. 2 is a top plan view.

I claim:

The ornamental design for a rotatable reflector for bicycles, as shown.
